Frederick Barker
ATTORNEY

UNITED STATES PATENT OFFICE.

MORRIS BERMAN, OF BROOKLYN, NEW YORK.

HOLDER FOR DOMES, GLOBES, AND LIKE OBJECTS.

Application filed August 28, 1925. Serial No. 53,008.

This invention relates to holders for domes, globes and like objects such as are used in conjunction with electric light fixtures, and my improvement is directed particularly to certain novel means of engagement between the holder and object.

Ordinarily, as is well understood, a dome, globe or like object is fastened to its holder by means of screws which are passed through

10 a pendent flange at the base of the holder and impinge against the object, taking under a peripheral flange thereon to afford the necessary support.

This means of attachment I have found 15 more or less uncertain and unsatisfactory, inasmuch as at least three screws have to be manipulated, and care must be exercised, in screwing them up, to avoid damaging the object.

20 Therefore, my invention consists, in brief, of a hinged L-flange segment upon the holder which can be swung outwardly to permit the introduction of a dome, globe or like object, and then said hinged L-flange segment can 25 be closed into circular formation with a corresponding fixed L-flange segment and secured, to thereby constitute an annular support by engagement with the annular flange with which the object is provided.

30 Other features and advantages of my invention will hereinafter appear.

In the drawing:

Figure 1 is an elevation of a holder for 35 globes, domes, and other objects partly broken away, and

Fig. 2 is an inverted plan view of the same showing the object holding means in an open position.

In said figures let 1 indicate a usual form 40 of holder adapted for connection with an electric light fixture, and having a skirt 2 which is provided with a base annular flange.

Said flange, which is L-shaped in cross section is in two segments, one segment, 45 indicated at 3, being integral with skirt 2, and the other segment, indicated at 4, being hinged at one end to the fixed segment, as at 5, and at its other end having means whereby it may be releasably engaged with 50 the fixed segment. As shown, the free end

of segment 4 is provided with a pivotal hook 6 adapted to engage a button 7 carried by the fixed segment near its free end.

As will be quite apparent, the radial or horizontal portion of the L-shaped flange 8 55 forms the supporting element for a dome, globe or like object by engaging under the annular flange or projecting portion with which such objects are provided.

The security of the engagement between 60 the holder and dome, globe or like object is assured upon locking the hinged segment to the fixed segment by fastening means such for example as those here shown, because the support thus afforded is annular and 65 co-extensive with the peripheral flange of the object to be supported.

Variations within the spirit and scope of 70 my invention are equally comprehended by the foregoing disclosure.

I claim:

1. A holder for domes, globes and like objects comprising a body having an annular, inturned flange entirely surrounding said body, for object engaging purposes, one segment of said flange being rigid with the body, and another segment hinged to said fixed segment, that it may be swung outwardly for the reception of an object, and closed upon said object to suspend it in co-action with said fixed segment, the hinged segment entirely closing the space between the globe and the holder.

2. A holder for domes, globes and like objects comprising a body having an annular, inturned flange entirely surrounding said body, for object engaging purposes, one segment of said flange being rigid with the body, and another segment hinged to said fixed segment, that it may be swung outwardly for the reception of an object, and closed upon said object to suspend it in co-action with said fixed segment, the hinged segment entirely closing the space between the globe and the holder, and mutually engageable fastening means respectively upon said fixed and hinged segments.

Executed this 24th day of August, 1925.

MORRIS BERMAN.
